(57) **CLAIM**

The ornamental design for a grounding connector, as shown and described.

DESCRIPTION

FIG. 1 is a perspective view of a grounding connector showing my new invention with a cable and screw not forming a part of the invention shown in dotted outline for orientation purposes;

FIG. 2 is a front elevational view thereof;

FIG. 3 is a left-side elevational view thereof;

FIG. 4 is a rear-elevational view thereof;

FIG. 5 is a right-side elevational view thereof;

FIG. 6 is a top-plan view thereof; and,

FIG. 7 is a bottom-plan view thereof.
